UNITED STATES PATENT OFFICE

169,400

CHECKERS GAME PIECE

George F. Wales, Kenmore, N. Y.

Application July 31, 1950, Serial No. 11,500

Term of patent 14 years

(Cl. D34—5)

To all whom it may concern:

Be it known that I, George F. Wales, a citizen of the United States, residing at 188 Doncaster Road, Kenmore, in the county of Erie and State of New York, have invented a new, original, and ornamental Design for a Checkers Game Piece, of which the following is a specification, reference being had to the accompanying drawing, forming a part thereof.

In the drawing:

Figure 1 is a perspective view of the game piece embodying my new design.

Figure 2 is a top plan view thereof.

Figure 3 is a side elevation thereof.

Figure 4 is a face view of the bottom side thereof.

Figure 5 is a transverse vertical section thereof, taken on line 5—5 of Figure 2.

I claim:

The ornamental design of a checkers game piece, substantially as shown.

GEORGE F. WALES.
